PIPE AND TUBING RACK

Walter B. Aggers, Coalinga, Calif.

Application August 27, 1936, Serial No. 98,281

4 Claims. (Cl. 211—60)

This invention relates to oil well derricks and equipment and accessories used in conjunction therewith, and has reference in particular to a new and novel systematized rack construction to expedite orderly handling of pipe sections and tubing.

Being generally conversant with the prior state of the art to which the invention relates, it is obvious that I am aware that so-called racks and equivalent storing and stacking devices are not new. As a matter of fact, it appears to be in keeping with good policy to point out here that it is quite common in this line of endeavor to provide so-called attendant-used tubing boards with projectible and retractable accessories and attachments to promote systematic and expeditious handling of tubing and pipe sections while pulling the well or reorganizing it after repairs have been made.

I may go even further and say that the tubing board which is generally occupied by a racking attendant or workman is mounted on the conventional derrick above the platform at an appropriate elevation so that the pipe and tubing sections as they are withdrawn from the well may be stacked perpendicularly in convenient rows. Although there are many makeshift arrangements including rigid projecting parts to facilitate such vertical stacking, prior patented structures have come into vogue disclosing the idea of foldable and other retractable and projectible adapters to facilitate racking and to avoid accidental breakage from the hoisting cable and traveling block. It follows, therefore, that my aim is to generally improve upon prior art structures in this classification by adopting and using what I believe to be a more satisfactory construction and adaptation of features.

The chief feature of the invention has to do with the use of hingedly or pivotally mounted rods selectively swingable from an out-of-the-way position over the tubing board, to a horizontal projecting position, said rods being associated with fixed keeper or retaining means calculated to accommodate different sized pipe sections.

Other features and advantages will become more readily apparent from the following description and drawings.

In the drawings, wherein like numerals are employed to designate like parts throughout the views:

Figure 1 is a horizontal section through a portion of a conventional oil well drilling derrick showing the conventional tubing board and illus-

trating it as equipped with the improved pipe-handling fingers and racking means constructed in accordance with my ideas.

Figure 2 is a vertical sectional view showing the assemblage of features appearing in top plan view in Figure 1.

Figure 3 is a section on the line 3—3 of Figure 1.

Figure 4 is a perspective view of a projectible and retractable pipe-handling finger constituting one of the improved features on the tubing board.

Figure 5 is a perspective view of the fixture or bracket used for anchoring the improved racking rods or members in place.

Figure 6 is a modified detail or part of the assemblage showing an I-beam retainer usable in some instances instead of the channel-shaped retainer shown in the other views.

In the drawings in Figure 1, the derrick, which is conventional, is denoted by the numeral 7 and the regular horizontal tubing board is denoted at 8. In practice this is disposed vertically and parallel above the customary base or platform (not shown) occupied by the various workmen and attendants in handling the job of withdrawing and disassembling the pipe sections and tubes, or coupling the parts and returning them to their normal positions after repairs have been made. As implied in the preceding description, it is obvious that a pump must be pulled every now and then in order to make repairs to the piston and other component parts, either of the pipe or the tubing structures as the case may be. This is generally done with a block and tackle, and as the tubing sections are withdrawn from the well and stacked vertically, some racking means is necessary to keep them in an orderly place and handy so that they can be retrieved and reassembled to put the well back in operating order.

Although it is by no means of most importance, it might be pointed out here that ordinarily on the tubing board 8 suitable projecting fingers are utilized to aid in initially suspending or holding the tube sections as they are withdrawn and before they are racked. The ordinary finger is rigidly mounted in place and interferes frequently with the operation of the block and tackle. The finger is used to let the tubing rest against it while taking off and putting on the tubing elevators which are used in pulling and putting tubing in wells. In the present arrangement the improved fingers are denoted by the numerals 9 and 10, respectively. The finger 9

comprises a slidable plate of the type shown in Figure 4. In other words, it is a simple plate of metal having a claw or U-shaped head 11 at its outer end to accommodate a pipe which is rested therein temporarily. It is also formed with a central longitudinal slot 12 and an offset bayonet slot 13. Through the instrumentality of these slots 12 and 13 and fastening screws 14 and 15, the finger is adjustably, that is, projectibly mounted on the tubing board at the proper place. When it is in use, it is in the position shown in Figure 1. When it is not in use, the fastenings 14 and 15 are loosened and by the agency of the slots 12 and 13 it can be adjusted or retracted to an out-of-the-way position. The companion finger 16 is a simple double-ended plate also slotted and held in place by suitable fastenings 17. Broadly, however, the point here is in having a projectible and retractable resting finger 20 to take the place of the ordinary rigid finger (not shown).

Of most importance, however, is the racking means. One of the features dominating this means is an anchoring or attaching bracket 17 which is a simple U-shaped member having its downturned ends threaded and secured by nuts or the like to the tubing board at a desired position. Secured also to the board outwardly of this and parallel thereto is the retaining unit 18 for the various selectively usable racking rods 19. Each rod is formed at one end into an eye 20 which is slidably and pivotally attached to the anchoring bracket 17. This allows the rods to be shoved close together or far apart as the case may be to accommodate pipe and tubing sections of different sizes. The sections are of a suitable length to project beyond the edge of the platform board 8 to accommodate a predetermined number of pipes or tubing sections as illustrated in Figure 1. Each rod is held projected and in readiness for racking purposes through the instrumentality of the retaining unit or device 18. One form of this is a simple channel-shaped member whose upstanding flanges 21 are provided with inclined keeper notches into which the rods 19 are swung and held temporarily in relative parallelism. One of the rods in Figure 1 is shown swung to operative position and three of the rods are swung back to an out-of-the-way position. The projecting rod at the right permits a series of pipe or tubing sections to be stacked thereagainst in vertical order as from the point A to the point B. This constitutes one row and the next row may start at C and extend on to D. Then the next rod is swung over in place and the sectional pipes or tubing are progressively and orderly stacked in readiness for reassembling when occasion requires.

So far as the part 18 is concerned, it may be described generically as a retaining unit provided with one or more upstanding flanges and an attaching portion, the flanges having keeper notches therein so that the pivoted rods 19 can be swung over and selectively engaged or seated in the desired opposed pairs of notches, as is obvious.

The modification shown at 18a in Figure 6 is merely for convenience of construction. Here instead of using a channel iron I found it expedient and practicable to use an I-beam. The web of

this is denoted by the numeral 23 and the flanges 24 are provided in upper and lower edges with properly slanting keeper notches 25. The principle of application and operation is the same, however, as that shown in Figure 1.

It appears to be new in this particular line of endeavor to provide a keeper unit 18 whether constructed as shown in Figure 1 or in Figure 6, the same having notched flanges and being disposed in parallelism to the anchoring or attaching fixture 17, there being fingers 19 pivoted on this part 17 and selectively engageable with the notches 22 or 25, as the case may be.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be restored to if desired.

I claim:

1. In a derrick, a tubing board structure adapted to be mounted on said derrick, a retaining member on said board, said retaining member comprising an attaching portion and upstanding flange portions, said flange portions being provided with a plurality of aligned keeper notches, a plurality of selectively usable rods engageable intermediate their ends with aligned pairs of said keeper notches, and means pivotally and slidably attaching the inner ends of the rods to the board structure.

2. In a structure of the class described, a fixed tubing board horizontally disposed, a rod like bracket secured to said board, a plurality of racking rods pivotally mounted on said bracket to swing into and from outwardly projecting relation to one edge of said board, a rack like retaining member secured to said board adjacent said edge thereof and having diagonal notches therein for receiving said rods to hold the latter in spaced apart relation, said rods being slidable on said bracket for engagement with selective notches to hold said rods in differently spaced relation.

3. In a structure of the class described, a supporting member, an elongated bracket on said member, a plurality of rods pivotally and slidably connected at one end to said bracket and an elongated member in front of and arranged parallel to the bracket and having a plurality of notches therein for receiving portions of the rods when the rods are swung over into engagement with the notched member.

4. In a structure of the class described, a supporting member, an elongated bracket connected with the supporting member, a plurality of rods supported for pivotal and sliding movement at one end on said bracket and a channel member connected with the supporting member in front of and paralleling the same and having aligned notches in its flanges for receiving the rods when the same are swung over into engagement with the channel member, said rods projecting from said supporting member when held in the notches.

WALTER B. AGGERS.
